UNITED STATES PATENT OFFICE.

VALENTINE SCHUCK, OF NEW YORK, N. Y., ASSIGNOR TO SUTRO BROTHERS BRAID COMPANY, OF NEW YORK, N. Y., A CORPORATION OF NEW YORK.

DESIGN FOR BRAID.

SPECIFICATION forming part of Design No. 36,118, dated October 21, 1902.

Application filed June 17, 1902. Serial No. 112,113. Term of patent 3½ years.

To all whom it may concern:

Be it known that I, VALENTINE SCHUCK, a citizen of the United States, residing at Manhattan borough, New York city, in the county 5 and State of New York, have invented a new, original, and ornamental Design for Braid, of which the following is a specification.

My invention relates to a new, original, and ornamental design for braid and is illustrated 10 in the accompanying drawings as showing a face view of the braid.

The leading feature of my design resides in a flat braid having wave-shaped edges, presenting the appearance of a series of flat balloon-shaped forms contracted at each end, with 15 the wave-crest of one edge of the braid out of vertical alinement with the wave-crest of the other edge of the braid and with the edges forming the wave slants parallel with one another. The flat balloon portions of the 20 braid are connected together by narrow flat necks which extend at an inclination.

As seen in the annexed drawing, the design 25 consists in having the edges of the braid wave-shaped and so formed that the crests of

the opposite waves are out of vertical alinement with one another, yet having approximately parallel slants. The waves of the braid have their crests at *a* and *b*, with slants at *c* and *d*, respectively. As indicated by 30 dotted lines 1 2 3, the opposite wave-crests *a b* are not directly or vertically opposite one another, but the wave slants *c* and *d* are parallel to one another, or approximately so, as indicated by dotted lines 4 4 and 5 5. 35

My design presents a flat braid having wave-shaped edges, and it has a novel, pleasing, and distinguished appearance.

What I claim as new, and desire to secure by Letters Patent, is—

The ornamental design for braid, substantially as herein shown and described.

In testimony whereof I have hereunto set my hand in the presence of two subscribing witnesses.

VALENTINE SCHUCK.
